UNITED STATES PATENT OFFICE.

FRANK W. WOOD, OF MONTCLAIR, NEW JERSEY, ASSIGNOR TO CHARLES CORY & SON, INC., OF NEW YORK, N. Y., A CORPORATION OF NEW YORK.

RUDDER CONTROL.

1,225,913.

Specification of Letters Patent. Patented May 15, 1917.

Application filed May 20, 1916. Serial No. 98,713.

To all whom it may concern:

Be it known that I, FRANK W. Wood, a citizen of the United States, residing at Montclair, in the county of Essex and State 5 of New Jersey, have invented certain new and useful Improvements in Rudder Control, of which the following is a specification.

This invention relates to steering gear for 10 vessels and has particular reference to steering gear adapted to be operated either by a motor or by manual power.

It is well known that in practically every 15 vessel having a motor operated steering gear the same is adapted so that it may be operated manually when occasion requires. The operation of substituting manual power for mechanical and vice versa to operate the steering gear is commonly known as "changing over". Heretofore in carrying out the 20 operation of changing over the construction or disposition of the parts of the steering gear required these to be in certain positions of adjustment before such changing over 25 could be made. Thus in an instance where the construction of the gear demanded that the vessel's rudder be in a neutral or midships position during the operation of changing over it is obvious that the said 30 operation required considerable time and was made difficult to perform in instances where the rudder was found extending to port or to starboard when the occasion arose for changing over.

35 In the present instance it is my purpose to obviate the requirement that the rudder or the parts of the said steering gear be in certain positions of adjustment before a change from one form of operating means 40 to the other can be made. To attain this end the invention embraces, among other features, the connecting of the manually and mechanically operated parts of a steering gear to a pair of tiller ropes; the adapting 45 of the said parts to be operated each independently of the other; and the disposal of said parts so as to operate initially on different portions of said ropes and at different directions with respect thereto.

50 With the above recited objects and others of a similar nature in view my invention consists in the construction, combination and

arrangement of parts set forth in and falling within the scope of the appended claims.

In the drawings—

Figure 1, is a contracted diagrammatic view of the complete invention.

Fig. 2, is a vertical transverse section taken through the pilot house and superstructure of a vessel showing the controllers 60 and indicator as these parts will substantially appear when in use.

Fig. 3, is a detail vertical longitudinal section taken through the stern portion of a vessel and showing the parts of this invention connected to the rudder.

In the embodiment shown the rudder 1, is disposed at the stern of the vessel 2, and the rudder post 3, which extends vertically upward from rudder 1 is mounted in the 70 stern portion of the vessel 2, in the ordinary manner. The quadrant 4, is fixedly secured to the upper portions of rudder post 3, and is provided with the usual means as for instance pins 5, to connect with the ends of 75 the tiller ropes 6 and 7, after the end portions of these have been disposed so as to extend in reverse directions through the usual grooves 8, in the curved side of the quadrant. The forward ends of the tiller 80 ropes 6 and 7 are connected in the usual manner to the drum 80, of the helm 9 which is disposed in the pilot house 10, or other suitable portion of the vessel, the arrangement being such that when the helm is 85 turned in either direction the ropes 6 and 7 will move relatively to each other and thereby operate to turn the rudder.

At a point between the helm 9, and quadrant 4, the ropes 6 and 7 are trained over 90 pulleys 11 and 12 the supports of which (not shown) are rigidly secured to the deck or other fixed portions of the vessel. From the pulleys 11 and 12 the ropes 6 and 7 pass around travelers 13 and 14 and are then re-trained over pulleys 11 and 12 as shown, thus placing a bight in the rope connections. The travelers 13 and 14 are supported by a pair of hangers 15 and 16 adapted to hold the said pulleys in alinement with pulleys 100 11 and 12. A guide bar 17, passes through openings made to receive it in the rear end portions 18 of the hangers and this guide bar is so disposed and connected to any suit-

able fixed portion of the vessel as to permit the hangers to slide thereon. Lateral extensions 19 on the rear end portions 18 of the hangers are disposed so as to bear on the 5 bar 17, and by their presence provide generous bearing portions for the hangers without materially increasing the size or weight thereof. A suitable means is provided for moving the hangers longitudinally of bar 17. For purposes of illustration I have 10 shown this means as comprising a screw 20 the ends of which are pinned in openings of hangers 15 and 16. A connection consisting of a spur gear 21, threaded on screw 20 and 15 journaled in a bracket 22 depending from the deck, and a pinion 23, may be established between the screw 20 and a reversible motor 24. The motor 24 may be an electric motor as shown or any other desired type. 20 Thus it will be seen that when the motor operates to turn pinion 23 and spur gear 21 screw 20 will operate traveler 13, for instance, to move away from or toward pulley 11, traveler 14 moving in the opposite direction, hangers 15 and 16 being spaced apart 25 a constant distance and therefore movable in unison. Now when the parts are arranged as shown in Figs. 1 and 2 it will be obvious that if the motor 24 be idle the turning 30 of the rudder may be effected by turning the helm 9, it being evident that the pull exerted on one of the tiller ropes by turning the helm in one direction will have no effect whatever on changing the positions of 35 the travelers 13 and 14 with relation to the pulleys 11 and 12. But when the helm is held against turning movement by a becket or otherwise suitably lashed, and the motor caused to operate in one direction a change 40 in the relative positions of pulley 11 and traveler 13, and pulley 12 and traveler 14 will be had. If the turning movement of screw 20 is such as will cause a movement of the traveler 13 in a direction away from 45 pulley 11, and move the traveler 14 toward pulley 12, then the movement on the part of the traveler 13 causes the same to exert a pull on the tiller rope 6 and the movement on the part of the traveler 14 slackens the 50 rope 7. The pull exerted on the rope 6, by the traveler 13 causes the quadrant 4 and rudder 1 to turn immediately in a clockwise direction and the movement of the quadrant takes up the slack of the rope 7, so that when 55 the operation of the motor 24 is reversed and a pull transmitted by the traveler 14 to the rope 7, the same will immediately cause the quadrant 4 and the rudder 1 to turn in a direction opposite to that last described. 60 In other words, the increase in length of the bight around traveler 13 provides a corresponding decrease in the length of the bight around traveler 14. Hence, both bights will remain taut throughout the shifting operation, so that when change is made to manual

steering the ropes will be in proper position to permit the immediate steering action. When the change is made the bights remain constant in length, the inactive motor forming a lock to prevent change in position of 70 the travelers. It will therefore be understood that power steering is had by varying the bight lengths of the tiller ropes, that portion of the ropes between the bight and the helm remaining unchanged in position, 75 while in manual steering the bight lengths remain constant, but the ropes shift both in the bights and such intermediate portions.

Thus it will be seen that the action produced on the tiller ropes by the travelers is 80 the equivalent to that which would be had by substituting for spur gear 21 a drum geared to pinion 23, and having the tiller ropes 6 and 7 wound thereon. But the provision of a drum would defeat the result had 85 with the present arrangement of parts because the helm 9, could not be operated without disconnecting the said drum from pinion 23.

The purpose of the present invention will 90 now be clear, it being evident that adjustment of the mechanically operable parts will not be necessary in order that the rudder may be operated manually; and in changing from manual to mechanical operation nothing further will be required than to secure the helm against rotation and then start the motor. It will also be evident that the change from mechanical to manual operation and vice versa may be made substantially instantaneously when the rudder is moving into any of its possible positions of adjustment, and when such change has been effected such movement of the rudder may be continued in any required direction. The 100 controller 25 is arranged in pilot house 10, and the controller handle 26 may be adjusted from the neutral into either of two positions. In the drawings the handle is shown in the neutral and when turned from this 105 position into contact with the point 27, current from the mains 28 and 29 flows in a positive direction through the conductors 30 and 31 through the limit switch 32, wire 33, coil 34 and reversing switch 35 and wire 36 110 to the main 28. When the handle 26 is adjusted into contact with point 37, the current flows in a negative direction through wires 30 and 38 to limit switch 32 and then through conductor 39 through coil 40 to reversing switch 35 and conductors 41—42 and 115 36, to a main. When the current flows in a positive direction the reversing switch 35 is operated in the usual manner to close motor circuit 43 so that the motor will be caused to turn in one direction, but when the current is caused to flow in a negative direction through reversing switch 35 and the circuit 43 of the motor the latter will operate in a 120 reverse direction.

The limit switch 32 is operated by oppositely disposed lugs 44 on a sector 45, carried by quadrant 4. These lugs are so positioned as to provide an intervening space 5 into which the lever 46 of switch 32 extends and the construction of the sector and the disposition of the lugs is such that these will operate the switch lever 46 to open the circuit of the relay switch when the rudder 10 is arranged in hard over positions.

The usual visual indicator 47 is arranged in the pilot house 10, a turnable contact maker 48 is geared to a rock arm 49 which is connected by a link 50 to quadrant 4, the 15 usual system of wiring 51 is employed for effecting the electrical connection or for providing the circuits between the contacts 52 and 53 of the contact maker and the levers 54 of the indicator 47. The purpose of this 20 construction being to indicate visually the position of the rudder with respect to the fore-and-aft line of the vessel at all times.

What I claim is:

1. The combination with the rudder of a 25 vessel, a manually operable steering element, and tiller connections extending between the rudder and said element for producing rudder movements, of power mechanism in permanent operative engagement with said connections intermediate the rudder and steering element and adapted to produce rudder movements when the mechanism is active and when said element is held stationary, the 30 length of the connections between rudder 35 and steering element remaining constant during mechanism operation.

2. The combination with the rudder of a vessel, of a manually operable steering element, tiller cable connections extending between the rudder and said element for producing rudder movements, said connections including a bight in each connection, and power mechanism for varying the bight 40 lengths when said element is held stationary, 45 said mechanism including a device in permanent operative engagement with each bight and movable rectilinearly by mechanism movements.

3. The combination with the rudder of a 50 vessel, of independent manual and power steering mechanisms adapted for non-concurrent operation, and separate rudder-operating connections extending directly from one of said mechanisms to the rudder, said 55 connections including a bight in each connection constant in length during activity of such mechanism, the other of said mecha-

nisms being in permanent operative engagement with said bights and adapted to vary the bight lengths.

60

4. The combination with the rudder of a vessel, of a manually operable steering element, tiller cable connections between the rudder and said element for producing rudder movements, said connections including a bight in each connection, and means including power mechanism whereby said bights will remain constant in length during manual steering and be varied in length during power steering.

70

5. In a vessel a steering gear including a quadrant connected to the rudder of the vessel, hand gear including a helm, oppositely disposed tiller ropes connecting the quadrant with the helm, a power gear including a 75 motor, oppositely disposed rotatable travelers permanently connected to the tiller ropes and means for connecting the travelers with the motor and operating to move the travelers rectilinearly when the motor 80 is in action, and to lock the travelers against bodily movement when the motor is at rest, whereby the operation of substituting hand power for motor power and vice versa to operate the tiller ropes and quadrant may be 85 performed while either of said gears is in any of its possible positions of adjustment.

90

6. In a vessel the combination of a quadrant connected to the rudder of the vessel, a hand gear including a helm, oppositely disposed tiller ropes connecting the quadrant with the helm, a power gear disposed at a point between the connected ends of the tiller ropes and including a motor, a controller further arranged adjacent to the 95 helm, oppositely disposed travelers permanently connected to the tiller ropes and means connecting the travelers with the motor, said means operating to move the travelers rectilinearly when the motor is in action, and to lock the travelers against bodily movement when the motor is at rest whereby the operation of substituting hand power for motor power and vice versa to operate the tiller ropes and quadrant may be 100 performed while either of said gears is in any of its possible positions of adjustment.
